MEDICINAL PLASTER OR BANDAGE

William M. Scholl, Chicago, Ill.

Application July 30, 1958, Serial No. 752,058

8 Claims. (Cl. 128—153)

This invention relates to improvements in a medicinal or surgical plaster or bandage and is particularly desirable as a digital bandage for application to a finger or toe to alleviate afflictions of the general character of excrescences, corns, calluses, warts, as well as other afflictions such as cuts or abrasions, although the device will have other uses and purposes as will be apparent to one skilled in the art.

In the past, many and various types of plasters or bandages of the pressure-relieving type have been developed, but in many cases these bandages while capable of transferring the pressure of an article of apparel or the like to healthy tissue surrounding an affliction, were of such construction that the pressure-eliminating portion of the plaster or bandage itself caused some irritation. In other cases, these bandages if the pressure-relieving portion had a cavity or aperture to receive an affliction, were of such construction that a medicament placed over the affliction would not be in sufficiently close proximity to the affliction, and frequently such items were of such construction that a sudden application of pressure directly over the affliction was not cushioned or rendered at least partially ineffectual by the plaster itself. In other instances, these formerly known bandages did not fit a particular portion of the body, such as a digit, with an effective nicety, but would overlap a digit and extend sidewise to an extent that the bandage would cause irritation to, or possibly be disrupted by adjacent digits.

With the foregoing in mind, it is an important object of the instant invention to provide a digital plaster or bandage in which the pressure-relieving portion of the device is provided with opposed edges substantially paralleling the side edges of the digit to which the bandage is applied.

Another object of the instant invention resides in the provision of a medical or surgical plaster or bandage having a body part or pad of cushioning material with an affliction-receiving cavity therein, and with a medicated plug or tab in the cavity and also providing a cushioning action.

A further feature of the invention resides in the provision of a plaster or bandage having a pressure-relieving portion of cushioning material with an affliction-receiving cavity therein, in which cavity is disposed a medicated tab in such manner and of such construction as to bring the medication into close proximity with the affliction itself.

Still another object of the instant invention is the provision of a plaster or bandage incorporating a pressure-relieving pad having an affliction-receiving cavity therein, and a medicated tab of napped fabric disposed in the cavity in such manner that the napping on the tab functions as a shock-absorbing medium against sudden pressures applied directly over the affliction.

While some of the more salient features, characteristics and advantages of the instant invention have been above pointed out, others will become apparent from the fol-

2

lowing disclosures, taken in conjunction with the accompanying drawing, in which:

Fig. 1 is a plan view of a plaster or bandage embodying principles of the instant invention;

5 Fig. 2 is a bottom plan view of the structure of Fig. 1;

Fig. 3 is a longitudinal vertical sectional view taken substantially as indicated by the line III—III of Fig. 1, looking in the direction of the arrows; and

10 Fig. 4 is an enlarged fragmentary vertical sectional view of the character of Fig. 3, but showing a slightly different form of construction.

As shown on the drawings:

The illustrated embodiments of the instant invention are purposely shown enlarged beyond their most usual size for purposes of clarity. It will be understood that in actual manufacture the bandage or plaster may be made of any desirable size, but in most instances will be made exceedingly smaller than the illustrations, so as to adequately fit around a digit such as a toe or finger.

15 The first illustrated embodiment of the instant invention, seen in Figs. 1, 2 and 3, includes an attaching strip 1 which is relatively narrow in its end portions, but which is preferably provided with an enlarged intermediate portion as indicated at 2. Throughout its entire length, 20 this strip is preferably provided on its under face with a pressure-sensitive adhesive spread 3. This attaching strip may be made of any suitable material but is preferably made of a waterproof material and is imperforate throughout. By way of example, the strip could be a thermoplastic film, a thin plastic-coated fabric, or the equivalent. It is preferably of a length to wrap entirely around a digit with the ends slightly overlapped.

25 Secured by the adhesive under surface 3 to the under side of the enlarged portion 2 of the strip 1 is a pressure-eliminating pad or body part 4. This may be made of any suitable cushioning material such as felt, foam latex, thermoplastic or chemical foam, or the equivalent. As seen best in Fig. 2, the forward and rear edges of the pad 4 are preferably arcuate or curvate as indicated at 5, 30 while the opposed side edges of the pad are preferably straight, as indicated at 6—6, these side edges therefore substantially paralleling the sides of a digit such as a finger or toe. The pad 4 itself may lie directly upon the digit but will not project beyond the digit in a manner to cause spacing between digits, irritation to an adjacent digit, or disruption or loosening of the pad by contact with an adjacent digit, as would be the case if the pad were completely circular. The pad is preferably provided with an affliction-receiving cavity 7 therein which

35 may be of any suitable size or shape, but which in the illustrated instance is shown in the form of an aperture, and the pad is of sufficient thickness that an affliction such as a corn or the like may be received within the cavity 7 and the pressure of an article of apparel transferred to adjacent surrounding healthy tissue. On its

40 under face, the pad is also preferably provided with a spread of pressure-sensitive adhesive as seen at 8 in Fig. 3, to better insure the pad remaining in its desired position during use.

45 As seen best in Fig. 1, the marginal portions of the pad 4 adjacent the rounded edges 5—5 thereof preferably project beyond the enlarged portion 2 of the strip 1. This facilitates proper positioning of the pad on the body of a user.

50 In order to relieve and aid in the cure of the particular affliction, a medicated plug or tab is preferably disposed in the affliction-receiving cavity of the pad 4 in position to overlie the affliction itself. This tab or plug may be held in position by the adhesive under surface 55 of the attaching strip 1, or it may be held in position by friction alone. As seen best in Fig. 3, the plug or tab comprises a fabric sheet 9 which is napped on one side

as indicated at 10, and preferably this napping is relatively heavy. In this particular embodiment of the invention, the napped side of the fabric is disposed uppermost, and on the smooth under side of the fabric a suitable medicament 11 is provided. While in the illustrated showing the medicament is in the nature of a spread on the under side of the tab in order to facilitate illustration, it will be understood that the pad might be impregnated with some suitable medication, if so desired. Further, it should be noted that the medicated tab is thinner or of less thickness than the cushioning pad 4 so as to leave space in the cavity 7 for reception of the affliction. The structure of the medicated tab brings the medicament in closer proximity to, or in contact with the affliction, whereby full benefit of the medicament may be acquired. In addition, it will be noted that the napping 10 on the fabric tab will provide a cushioning effect and act as a shock absorber if through inadvertence sudden pressure or a blow is applied to the outside of the attaching strip 1 directly over the affliction. Sometimes, in the past with previously constructed plasters or bandages, irritation of the affliction was caused by wearing apparel forcing the cover or attaching strip inwardly in the region of the affliction-receiving cavity, so that there was a disagreeable amount of rubbing on the affliction itself. Such irritation or rubbing with the instant invention will be eliminated by virtue of the yielding character of the napping on the medicated tab.

In Fig. 4 I have illustrated a slightly different arrangement, wherein the general structure is the same as above described. In this instance, however, the medicated tab is reversed in position, with the fabric portion 9 uppermost, and the napping 10 depending therefrom, the medicament 11 being applied to the napping 10 rather than to the smooth side of the fabric. This may be more desirable in connection with certain types of afflictions.

In use, the instant invention may be easily and quickly applied to a digit over an affliction. Assuming a corn to be the cause of trouble, it is a simple expedient to place the plaster or bandage so that the corn is directly beneath the medicated tab within the cavity 7, and wrap the end portions of the attaching strip 1 around the toe. The waterproof nature of the attaching strip permits the user to bathe the foot and leave the plaster or bandage in position.

From the foregoing, it is apparent that I have provided a simple form of plaster or bandage for digits of the pressure-relieving type, which not only fits the digit in a neat and effective manner, transfers pressure to healthy tissue around an affliction, but also brings medicament closer to the affliction and renders a shock-absorbing service against blows or pressure applied directly over the affliction, to a considerably greater extent than was possible with similar appliances made heretofore. Obviously, the instant invention with its improved features may be very economically manufactured, and is extremely durable.

It will be understood that modifications and variations may be effected without departing from the scope of the novel concepts of the present invention.

I claim as my invention:

1. In a surgical bandage, a body part of cushioning material having curvate front and rear edges and straight

side edges to parallel a digit, said body part having an opening therein, a relatively narrow attaching strip having a widened intermediate portion to overlie said body part and carrying a pressure sensitive adhesive under surface, and a napped soft fabric plug thinner than said body part and carrying a medicament on its under surface attached to said attaching strip inside said opening.

5 2. In a surgical bandage, a body part of cushioning material having curvate front and rear edges and straight side edges to parallel a digit, said body part having an opening therein, a relatively narrow attaching strip having a widened intermediate portion to overlie said body part and carrying a pressure sensitive adhesive under surface, and a napped soft fabric plug thinner than said body part and carrying a medicament on its under surface attached to said attaching strip inside said opening, said body part also carrying a pressure sensitive adhesive on its under surface and projecting beyond the widened portion of said attaching strip at the margins adjacent 10 20 the curvate edges.

15 3. In a surgical bandage, an attaching strip, a pad of cushioning material on said strip, said pad having an opening therein, and a medicated tab of less thickness than said pad in said opening and comprising a napped fabric.

25 4. In a medicinal plaster or bandage, a relatively thick pad of cushioning material having an opening therein to receive an affliction, means to attach said pad to the body of a user, and a tab thinner than said pad comprising a napped fabric carrying medicament on the lower face thereof and disposed in said opening.

30 5. In a medicinal plaster or bandage, a pad of cushioning material having a cavity therein to receive an affliction, means to attach said pad to the body of a user, and a tab of napped fabric thinner than said pad in said cavity and carrying a medicament exposed on the under surface of said tab.

35 6. In a medicinal plaster or bandage, a pad of cushioning material having a cavity therein to receive an affliction, means to attach said pad to the body of a user, and a tab of napped fabric thinner than said pad and disposed in said cavity with the napped side uppermost, said tab carrying a medicament exposed to the affliction on the opposite side of said tab.

40 7. In a medicinal plaster or bandage, a pad of cushioning material having a cavity therein to receive an affliction, means to attach said pad to the body of a user, and a tab of napped fabric thinner than said pad and disposed in said cavity with the unnapped side of the fabric uppermost, said tab carrying a medicament on the napped lower side thereof to contact the affliction.

45 8. In a medicinal plaster or bandage, an elongated thin waterproof attaching strip carrying pressure sensitive adhesive on its under face, a pad of cushioning material having an affliction receiving cavity therein and an adhesive under face carried by said strip, and a fabric tab heavily napped on the upper side in said cavity against the adhesive on said strip to overlie the affliction received in said cavity, said tab being thinner than said pad and carrying a medicament exposed on its under surface.
